FOOD HANDLING APPARATUS

George R. Wood, Montreal, Quebec, Canada, assignor to Toledo Scale Company, Toledo, Ohio, a corporation of New Jersey

Application April 12, 1943, Serial No. 482,765

2 Claims. (Cl. 146—102)

1

This invention relates to food handling apparatus of the type in which a commodity to be sliced is reciprocated past the edge of a circular rotary knife, being slid along the face of a gauge plate which is substantially parallel to the plane of the edge of the knife and is adjustable in a direction substantially perpendicular thereto to vary the thickness of the slice severed during each stroke, and more particularly to the commodity-carrying member of such a machine and to means for holding commodities in place on such a commodity-carrying member.

The commodity-carrying member of a slicing machine, usually called the commodity tray or trough, comprises a trough-like structure which is mounted for reciprocation on a slicing machine base to carry the main piece of commodity past the exposed edge of the knife. A commodity tray is usually provided with a commodity clamp which may be fed transversely across the commodity tray toward the plane of the knife by means of a spring to force the commodity against the gauge plate as it approaches and passes over the edge of the knife. Such a clamp has a vertical forward face which is substantially parallel to the face of the gauge plate and the plane of the knife and serves its purpose excellently when the commodity has a substantial cross section so that it can be pushed from the rear. A clamp of this type may also have commodity-engaging prongs on its lower edge which can be forced downwardly into a flat commodity, such as a bacon slab, to feed the commodity toward the knife. However, many commodities, such as bologna, liver sausage, thuringer, and others, have a length substantially greater than their cross section and cannot be fed by pressure at the rear because they would buckle and not remain flush against the face of the gauge plate. Neither can they be fed by engagement with the commodity engaging prongs, used for feeding a commodity such as bacon because, since many of them are round in cross section, they would not be held stationary.

It is an object of this invention to provide a commodity clamp having commodity engaging members which will serve to hold a small cylindrical-shaped commodity firmly in place so it may be fed by spring action.

It is another object of this invention to provide a commodity clamp having commodity engaging members located to pierce and hold a commodity of small cross section in the angular intersection of the faces of a trough-shaped

commodity tray and to feed such commodity toward the knife blade.

It is a further object of this invention to provide a commodity clamp having a section which can be frictionally engaged with the surface of a commodity of small circular cross section to hold the commodity stationary and to permit it to be fed manually toward the gauge plate.

It is a further object of this invention to provide a commodity clamp for use in manual feeding of commodities of small circular or other cross section which will assist in holding the commodities firmly and will also protect the hands of the operator.

More specific objects and advantages are apparent from the description, in which reference is had to the accompanying drawing illustrating a preferred form of device embodying the invention.

20 In the drawing:

Fig. I is a view, in elevation, of a slicing machine employing a commodity clamp embodying the invention.

Fig. II is a fragmentary enlarged view, in elevation, of a commodity clamp embodying the invention and in a different operating position than that shown in Fig. I.

Fig. III is an enlarged vertical sectional view, taken substantially on the line III—III of Fig. I.

30 The specific drawing and the specific description that follows merely disclose and illustrate the invention and are not intended to impose limitations upon the claims.

A slicing machine, which is adapted to employ 35 a commodity clamp embodying the invention, comprises a base 10 on which is erected driving and journaling means for a rotary circular knife 11 which is guarded by means of a knife guard 12, also mounted on the base, and a gauge plate 13 mounted on the base with its face in a plane parallel to the plane of the edge of the knife 11 and with its edge closely adjacent the edge of the knife 11. The gauge plate 13 is adjustable on a line perpendicular to the plane of its face by 45 means of a gauge plate adjusting and indicating knob 14 which is located at the front of the base 10. A commodity tray carriage 15 is mounted for reciprocation on the base 10 past the edge of the knife 11, having a handle 16 by which it is manually reciprocated. The commodity tray carriage 15 mounts an angular trough-shaped tray 17 on which commodities are carried.

At the rear edge of the commodity tray 17 there is located a transversely extending shaft 18 which is mounted in two ears 19 secured to

the tray 17. An angular commodity clamp arm 20 is slidably mounted on the rod 18 for movement transversely across the commodity tray 17 on a line perpendicular to the face of the gauge plate 13. A spring 21 surrounds the shaft 18, being engaged between one of the ears 19 and the portion of the arm 20, which surrounds the shaft 18, both to urge the arm toward the knife and to swing it in a counterclockwise direction (Figs. I and II) downwardly toward the commodity tray 17.

A commodity clamp 22, which comprises a stamped plate 23 having two turned-over ends 24 and 25 and a turned-over flange 26, is swivelably mounted in a hub 27 formed on the end 15 of the arm 20 with the face of the plate 23 in a plane parallel to the gauge plate 13 and knife 11. The clamp 22 is swiveled in the hub 27 by means of a pin 28, the head of which fits into an aperture 29 in the plate 23 and which serves as an axis for a disk 30 which is riveted to the rear face of the plate 23 and located in a counterbore 31 in the hub 27. The pin 28 is forced into the hub 27 and thus remains stationary, permitting the disk 30, and plate 23 riveted thereto, to revolve. A plurality of commodity engaging points 32 are riveted to the forward face of the plate 23 to engage the rear of commodities to be pushed against the face plate 13 and knife 11. A U shaped, pronged member 33 is riveted to the turned-over flange 26 of the plate 23 and two slides 34, which extend below the points of the pronged member 33, are riveted to the ends 24 and 25 of the plate 33 at the ends of the flange 26. The pronged member 33, when the commodity clamp 22 is swiveled slightly more in a clockwise direction than shown in Fig. I, serves to engage the upper surface of commodities, such as bacon, and to feed such commodities toward the gauge plate. The slides 34 hold the commodity clamp with the points of the pronged member 33 out of engagement with the bottom plate of the commodity tray 17 to prevent damage to the points of the pronged member 33 or to the commodity tray.

At the lower portion of the turned-over side 25 of the plate 23 there is located a series of commodity engaging prongs 35 which are shown in Fig. I as engaged in a sausage-like commodity 36. The action of the spring 18 forces the arm 20 in a counterclockwise direction inserting the prongs 35 into the commodity 36 and also pushes the arm 20, commodity clamp 22 and engaged commodity toward the gauge plate 13 while holding the commodity in the corner of the commodity tray 17. Thus the commodity clamp holds the commodity against rotation, forces it firmly into the corner of the commodity tray to prevent its buckling, and feeds it against the face of the gauge plate to insure even, parallel slices being severed.

In Fig. II the commodity tray is shown swung

through 180° with the warped or turned-over end 24 of the plate 23 shown located in position to hold a commodity 37 having a circular cross section in the corner of the commodity tray 17. 5 This is particularly useful when the commodity is too small in diameter to enable the use of the prongs 35, or when it is too soft to be fed forward by the engagement of the prongs 35 therein (in an exceedingly soft commodity, the prongs 10 would merely rip the commodity rather than feed it). In this event the clamp 22 is used only to hold the commodity 37 in the corner of the tray to prevent its buckling and the commodity is fed forward manually, the plate 23 serving as a guard for the operator's fingers.

Because the arm 20 is resiliently forced in a counterclockwise direction, and the commodity clamp 22 is swivelable, the two ends 24 and 25 with their respective commodity engaging surfaces, or members, may be adapted to hold commodities of various cross sections for proper slicing and feeding—either automatic or manual.

The embodiment of the invention that has been disclosed may be modified to meet various requirements.

Having described my invention, I claim:

1. Commodity feeding means for a slicing machine having a commodity carrier with two angularly intersecting sides comprising a pusher plate and means for moving said plate across said carrier, said plate having a face lying in a plane substantially perpendicular to the direction of movement of said plate, and having commodity engaging members extending from its edges in at least two different directions, all of said engaging members lying in substantially the same plane, said plate being swivelably mounted on an axis substantially parallel to its direction of movement and having at least one smooth surfaced relieved corner having a surface of substantial width parallel to the sides of the carrier positionable in the corner formed by the intersecting sides of said commodity carrier to form with said sides a guide through which a commodity of small cross section may be fed and resilient means for urging said plate toward such corner.

2. A commodity clamp for a slicing machine having a V-shaped commodity carrier, comprising a generally rectangular pusher plate fitted with commodity engaging members on its face and some of its edges and mounted for reciprocation along said V-shaped carrier with its face perpendicular to its path of movement, said plate being rotatable to present any of its edges to the surface of said carrier and having one of its edges formed with a smooth warped surface of substantial width adapted to cooperate with the corner of said V-shaped carrier to form a funnel shaped guide through which commodities may be manually fed.

GEORGE R. WOOD.
